UNITED STATES PATENT OFFICE.

NEWTON ROGERS AND JAMES A. WHARRY, OF TERRE HAUTE, INDIANA.

DYNAMO-SPEEDER FOR GAS-ENGINES.

SPECIFICATION forming part of Letters Patent No. 403,376, dated May 14, 1889.

Application filed August 22, 1888. Serial No. 283,448. (No model.)

To all whom it may concern:

Be it known that we, NEWTON ROGERS and JAMES A. WHARRY, of Terre Haute, in the county of Vigo and State of Indiana, have invented certain new and useful Improvements in Dynamo-Speeders for Gas-Engines; and we do hereby declare that the following is a full, clear, and exact description of the invention, which will enable others skilled in the art to 5 10 15 20 25 30 35 40 45 50 55 60 65 70 75 80 85 90 95 100 which it appertains to make and use the same, reference being had to the accompanying drawings, and to the letters of reference marked thereon, which form part of this specification.

Our invention relates to improvements in dynamo-speeders for gas-engines; and the object of our improvement is to provide a ready means for obtaining the igniting-spark during the starting of the engine by turning the fly-wheel thereof by manual power. As gas-engines are usually started by turning the fly-wheel by hand-power or other outside force, the speed is at first quite slow—too slow, in fact, to create a sufficient current by the dynamo to provide an igniting-spark. If the dynamo be speeded sufficiently high at this slow speed of the engine, its speed and consequent resistance would be unnecessarily great when the engine is running at its working rate; hence it is necessary to provide means by which the speeding of the dynamo can be changed at these times, and this I accomplish by means of the mechanism illustrated in the accompanying drawings, in which—

Figure 1 is an elevation. Fig. 2 is a vertical section through the shaft and dynamo belt-pulley, showing its connection to the shaft.

Similar letters refer to similar parts in both figures.

A is the main shaft of the engine, upon which is mounted the fly-wheel W and the belt-pulley P, for operating the dynamo. This pulley operates the dynamo-pulley D, journaled in the frame B, carrying the dynamo, by means of a belt, Y. The pulley P is loose upon shaft A, and is turned by it through the medium of a spring pawl-connection.

E is the pawl-lever, pivoted at G.

F is the spring attached to the pulley, tending to hold the pawl in the notches I on the shaft.

H is the pawl end of the lever E, the other end being formed into the shape of a handle. The fulerum G is a pin secured in one of the spokes of the loose pulley.

J is a loose wheel or idler, mounted on a spindle, S, which can be moved along a slot in an arm, K, supported by the dynamo-frame.

On moving the idler to the bottom of the slot it forms a friction-connection between the fly-wheel W and the dynamo-pulley D. The fly-wheel, which is keyed to the shaft, is turned by hand through the medium of a crank, L, and handle N. This crank is provided at its one end with a screw-thread, M, which enters a thread in the end of the shaft.

The operation of our device is as follows: The idler J is brought into contact with the fly-wheel and dynamo-pulley, the crank is screwed into the shaft, and is turned by hand. As the fly-wheel is of greater diameter than the belt-pulley on the shaft, its rim velocity is higher, and this velocity is communicated to the dynamo by means of the fly-wheel, idler, and dynamo-pulley, the speed being sufficient to create an igniting-spark. During this time the dynamo-pulley D is turning the belt-pulley P at a higher angular velocity than that of the main shaft, owing to the respective sizes of D and P, and consequently the tapered end of pawl H will trip in the notches I on the shaft. When the engine arrives at its proper speed, the crank is automatically unscrewed from the shaft by holding it stationary in the hands, the idler J is thrown out and locked out of gear with the fly-wheel, and, the pawl H catching in one of the notches I of the shaft, the belt-pulley will turn with the shaft, and thus operate the dynamo-pulley D.

What we claim, and desire to secure by Letters Patent, is—

1. In combination with the fly-wheel of a gas-engine, a friction-wheel mounted adjustably in a slotted standard, and a speed-pulley on a dynamo-shaft, said friction-wheel being adapted to transmit motion from the fly-wheel to said speed-pulley and to be thrown out of gear by movement in said slot, substantially as described.

2. In a gas-engine, the combination, with the main shaft, fly-wheel thereon, and friction

connections between said fly-wheel and the speed-pulley, of a dynamo, a crank screw-threaded into the end of the main shaft by means of which the shaft and dynamo are turned in starting the engine, and which automatically unscrews from the shaft when the engine attains a normal speed, substantially as described.

3. In combination with the main shaft of a gas-engine, a dynamo operated thereby, and a crank screw-threaded into the end of the shaft, said crank automatically unscrewing itself from the shaft when the speed of the shaft exceeds the speed with which the crank is turned manually, substantially as described.

4. In combination with the main shaft of a gas-engine, a fly-wheel attached thereto, speed-connections between said fly-wheel rim and the spindle of a dynamo, a loose pulley

on said shaft held in connection between said pulley and the spindle of the dynamo, a crank for turning the main shaft manually, all arranged substantially as described, whereby, when the shaft is operated manually, the dynamo receives its motion from the rim of the fly-wheel, and when the engine attains its normal speed the dynamo may receive a slower relative speed from the shaft-pulley, substantially as set forth.

In testimony that we claim the foregoing as our own we affix our signatures in presence of two witnesses.

NEWTON ROGERS.
JAMES A. WHARRY.
